UNITED STATES PATENT OFFICE.

THOMAS J. HUDSPETH, OF PHOENIX, ARIZONA.

WIRE-FENCE-STRETCHING APPARATUS.

Application filed April 20, 1923. Serial No. 633,438.

To all whom it may concern:

Be it known that I, THOMAS J. HUDSPETH, a citizen of the United States, residing in the city of Phoenix, county of Maricopa, and State of Arizona, have invented certain new and useful Improvements in Wire-Fence-Stretching Apparatus; and I do hereby declare the following to be a full, clear, and exact description of the invention, such as will enable others skilled in the art to which it appertains to make and use the same.

This invention relates to means adapted for use in connection with the erection of wire fences, and more specifically to mechanism whereby the fence wire is clamped and held against the fence post, while being secured in position.

In the erection of fences where the barrier is formed of mesh wire secured to posts, it has always been a difficult operation to connect the wires to the supporting post while, at the same time, retaining the wires under sufficient tension to keep them sufficiently straight after connection, whereby to not only present a neat appearance, but to result in the conservation of considerable material.

The object of my invention, therefore, is the provision of means whereby the above-referred to purpose may be easily carried out with a minimum of labor and a maximum of efficiency, and, at the same time taking out the undesirable curvature which is present in the wire because of the fact that it is wound in the rolled condition in which it is vended.

Other objects of this invention will be made apparent in the following specification, when read in connection with the accompanying drawings which form a part thereof.

In said drawings,

Fig. 1 is a perspective view of a fence being constructed by the utilization of my devices,

Fig. 2 is a fragmentary top view of the construction shown in Fig. 1, and

Fig. 3 is a fragmentary sectional view of one of the clamping members.

It is the customary practice to vend mesh wire fencing in large rolls which are taken to the scene of operation and the fence sections are then taken off as desired. One end of the wire on the roll is secured to a post, and the roll is usually carried past three or four posts and, in position to be affixed to

the posts, is then stretched before being secured in position. This stretching operation is necessary, not only for the purpose of keeping straight the longitudinal strands of the wire, but also for the purpose of taking out the curvature or "kinks" caused by the wire being left for some time in rolled condition.

Referring specifically to the drawings, showing the method of utilization of the device as comprised in my invention, let it be assumed that the wire 1 has already been secured to a post, and it is desired to secure it, in proper and straightened condition, to the posts A, B, C and D. Under these circumstances the wire roll E is stood upon end at some point approximately in a line between the posts A and B, and a rounded shaper roll 2, which may be of any material, is positioned adjacent to roll E, and approximately in parallelism therewith, as illustrated in Figs. 1 and 2, the shaper 2 being placed in a reverse loop 3 formed in the wire 1, it being noted that the curvature of the wire in the loop 3, where it surrounds the shaper 2, is directly opposed to the curvature of said wire as it is wound upon the roll E.

The clamping stave 4, of any desired material, and preferably of rounded contour, is positioned between the roll E and the shaper 2 and, as shown in the drawings, at the rear of the section of wire extending between the shaper 2 and the roll E. The stave 4 is preferably provided with a plurality of aligned apertures 5, 5, and with a rear backing plate 6, shaped to the contour of the rear face thereof. Secured to the stave 4 is a hook member 7, here shown as bifurcated, the two legs 8, 8 thereof extending through the apertures 5 in the stave and being screw-threaded to receive the nuts 9, 9 which hold them in position.

To the post A is secured a draft mechanism, preferably carrying a chain 10, connected to the hook 7. This mechanism may be of any suitable construction, but is here shown as comprising a chain pulley 11, upon which the chain 10 is wound, and a ratchet 12, adapted for actuation by a hand lever 13, to tighten the chain 10, in a manner which will be clearly understood. A link 14, is secured to the chain 15, which surrounds the post A.

With the device in position, as shown in Figs. 1, and 2, it is obvious that a proper manipulation of the lever 13 will serve

to tighten the chain 10, resulting in pulling the stave 4 forcibly against the section of wire between the shaper 2 and the roll E. Such action will tend to cause the shaper 2 to roll slightly to the right, and tighten the wire 1 opposite the posts B, C and D, at the same time tensioning the portion 3 around the shaper 2, and taking out or neutralizing the undesirable curvature caused by the wire having remained for some time in the roll E.

While the wire 1 is stretched and straightened as above described, and held in position, the sections are then secured to the posts B, C and D by staples, or in any other suitable or convenient manner, and the wire between the posts will be found to be perfectly straight, with the undesirable bulge eliminated. Obviously the same process is carried out with other posts, until the fence is completed.

A material advantage incident to the use of my invention is that only one operator is necessary in the whole operation, as will be clearly apparent. The roll E, after the shaper 2 and the stave 4 have been placed in position and connected to the chain 10, will be self-supporting, and the operator is then free to manipulate the lever 13. As soon as the necessary tightness of the chain 10 has been attained, the operator secures the wire 1 to the posts B, C and D, the ratchet 12 meanwhile holding the instrumentalities in operating position. In this manner, after one end of the wire fabric is firmly secured to a properly braced post, the roll E may be led past a sufficient number of posts to unwind approximately forty rods of the fabric, the fabric then clamped at the otherwise unattached end as described, and then secured to the posts.

Obviously any suitable method for connecting the stave 4 to the draft mechanism may be employed and I am not limited to the embodiment herein shown, nor to any other modification falling within the scope of the appended claims.

I claim,

1. A stretching mechanism for wire fabrics secured at one end and being delivered from a roll, comprising a shaper positioned in a loop between the roll and the end of the fabric, a stave positioned between the roll and the shaper and bearing against the fabric therebetween, and means for drawing the stave against the body of the fabric, substantially as described.

2. In combination with the wire fence fabric wound upon a roll and secured at one end, a shaper positioned in a reverse

loop formed in the body of the fabric, a stave positioned between the roll and shaper and bearing against the section of the fabric connecting the roll and the shaper, and means for pulling the stave toward such shaper and toward the body of the fabric, substantially as described.

3. In combination with a wire fence fabric wound upon a roll and secured at one end, a shaper mounted adjacent the roll and having the fabric wound therearound, in a direction opposite to the wind of the fabric upon the roll, a stave mounted between the roll and shaper and behind the fabric connecting the roll and shaper, and means for drawing the stave toward the shaper and toward the main body of the fabric, substantially as described.

4. In combination with a wire fence fabric wound upon a roll and secured at one end, a shaper mounted adjacent the roll and having the fabric wound therearound in a direction opposite to the wind of the fabric upon the roll, a stave mounted between the roll and shaper and behind the fabric connecting the roll and shaper, and means for drawing the stave toward the shaper and toward the main body of the fabric, said means being adapted to detachably hold said stave against said shaper, substantially as described.

5. In combination with a wire fence fabric wound upon a roll and secured at one end, a shaper mounted adjacent the roll and having the fabric wound thereon in a direction opposite to the wind of the fabric upon the roll, a stave mounted between the roll and shaper and behind the fabric connecting the roll and shaper, and a draft device secured to said stave and adapted to draw it towards said shaper, substantially as described.

6. In combination with a wire fence fabric wound upon a roll and secured at one end, a shaper mounted adjacent the roll and having the fabric wound thereon in a direction opposite to the wind of the fabric upon the roll, a stave mounted between the roll and shaper, and a draft device secured to said stave and adapted to draw it towards said shaper, said device comprising a chain secured to said stave, a chain pulley mounted on a rigid support in alignment with the body of the fabric and engaging said chain, and means for rotating said pulley to wind up said chain, substantially as described.

In testimony whereof I affix my signature.

THOMAS J. HUDSPETH.
